ATTORNEY.

UNITED STATES PATENT OFFICE

133,638

DESIGN FOR AN ARCTIC OVERSHOE

Herman Arnoff, New York, N. Y.

Application July 25, 1942, Serial No. 107,675

Term of patent 3½ years

To all whom it may concern:

Be it known that I, Herman Arnoff, a citizen of the United States of America, residing in New York city, county of New York and State of New York, have invented a new, original, and ornamental Design for an Arctic Overshoe, of which the following is a specification, reference being had to the accompanying drawing, forming part thereof.

Fig. 1 is a front perspective view of an arctic overshoe showing my new design.

Fig. 2 is a bottom perspective view thereof.

Fig. 3 is a rear view thereof.

I claim:

The ornamental design for an arctic overshoe, substantially as shown.

HERMAN ARNOFF.
